UNITED STATES PATENT OFFICE.

HARRY BEISER, OF DETROIT, MICHIGAN.

KEY MACHINE.

Application filed February 14, 1925. Serial No. 9,094.

My invention relates to key machines, shown in the accompanying drawings and more particularly described in the following specification and claims.

5 The primary object of this invention is an improvement upon that described in my pending application for patent, Serial No. 625,453, filed March 16, 1923.

One feature of this invention consists in 10 means for cutting the "ward" grooves in malleable keys, also in providing adjustable and slidable means for bringing the key blank into proper position for forming the ward groove.

15 A further object of the invention is to provide means for cutting "double bit" keys—the arrangement being such that the shank of the key is gripped by the vise so that the distance from the center of the shank to the 20 outside of the bit is the same as in the pattern key—a recess being provided in the vise to receive one of the bits while the other bit is being cut.

A further object of the invention is a 25 swinging and sliding vise supporting frame—the construction being such that it is adapted to swing over the guide posts—aligned with the respective cutters—that it may be shifted from the extreme left to the 30 extreme right hand side of the machine, or vice-versa, as required.

Another feature of the invention relates to the duplex guide, corresponding with the duplex cutter, whereby grooves may be 35 formed in both sides and outer edges of the key bit.

Another feature consists in the means provided for alternately locking the high and low speed pulleys to the shaft.

40 Another feature consists in the means for moving the key vise in the frame for cutting edge grooves in Yale or like constructed keys.

With the foregoing and other objects in 45 view which will appear as the description proceeds the invention further resides in the combination and arrangement of parts and in the details of construction hereinafter described and claimed it being understood that 50 changes may be made in the precise embodiment of the invention herein disclosed without departing from the spirit of the same.

In the drawings accompanying this specification:

55 Figure 1 is a plan view of the machine, one end of the operating lever being broken

away to accommodate the view upon the sheet.

Figure 2 is an end elevation of the machine showing parts in cross-section taken 60 on or about line 2—2 of Figure 1 to more clearly disclose the construction.

Figure 3 is a fragmentary perspective view showing the vise for holding double bit 65 keys.

Figure 4 is a fragmentary perspective view of the lower member of the vise, shown in Figure 3.

Figure 5 is a fragmentary cross-sectional view—taken on or about line 5—5 of Figure 70 1—through a portion of the sliding and swinging frame and swinging lever for manually operating the same.

Figure 6 is a fragmentary cross-sectional view—taken on or about line 6—6 of Figure 75 1—showing the means for alternately locking and releasing the high and low driving pulleys to the drive shaft.

Figure 7 is a perspective view of the vise 80 for holding the key blank when cutting ward grooves.

Figure 8 is an end elevation partly in cross-section taken on or about line 2—2 of Figure 1, showing the laterally slidable frame carrying the key and key blank vises 85 at the outer limit of its movement as distinguished from the position shown in Figure 2—the view also shows in dotted lines the vises and frame tilted that they may pass the guide post in travelling from the extreme right to left-hand side of the machine or vice-versa.

Figure 9 is a cross-sectional view through the vise shown in Figure 7, showing a key bit 90 clamped between its adjustable jaws.

Referring now to the letters of reference 95 placed upon the drawings:

A indicates the bed frame of the key machine which may be bolted to a table, bench or other suitable support—not shown.

B denotes a movable frame adapted to slide laterally in the bed frame A, consisting of a pair of end rails B¹, B²—having inwardly directed flanges B³ extending into transverse grooves formed in the end walls 105 of the bed frame,—coupled together by rods B⁴, B⁵, B⁶, to which they are rigidly secured.

C designates a duplex vise frame pivoted to the rod B⁴ and slidable thereon having a channel groove on the underside of its 110 free end to receive the rod B⁵ upon which the frame rests. Integral with the frame C

are two spaced upstanding posts C^1 , C^2 , forming the lower stationary jaws of a pair of key vises. C^a , C^b , are movable jaws—of inverted U-shaped form in cross-section—5 respectively slidable upon a contracted upper extension c of the posts C^1 , C^2 . The lower stationary jaws of each vise is provided with a serrated recess—as indicated at c^1 to receive the shank of a key; the post is 10 also cut away as indicated at c^2 to receive one of the bits of a double bit key.

D, D^1 , indicate a pair of thumb screws extending through the movable vise jaws to engage the respective stationary posts. 15 Sleeved upon the thumb screws are springs D^a —the purpose of which is to open the movable jaw when the nuts are adjusted to release the key, or key-blank gripped between the jaws.

20 E, E^1 , E^2 , denote rotary cutting tools spaced apart upon a shaft F, supported in suitable bearings G, extending upwardly from the bed frame.

H and H^1 designate high and low speed 25 driving pulleys mounted upon the shaft G.

I indicates a longitudinal slidable key lodged in a groove formed in the driving shaft adapted when shifted to alternately lock the respective pulleys H and H^1 to the 30 driving shaft—as indicated in full and dotted lines in Figure 6. F^1 indicates a flange formed on the shaft F grooved to receive a split ring f to secure the slidable key I, against accidental release. F^2 35 denotes a nut engaging the end of the shaft to retain the driving pulleys H and H^1 upon the shaft.

Secured to one end of the shaft F is a 40 tool E^3 adapted to cut ward grooves in malleable keys.

Mounted in a slot formed in the end rail B^2 and co-operating with the cutter E^3 is a key vise J comprising two jaws J^a , J^b , connected together by pins J^1 , J^2 , secured to 45 one of the walls and projecting into apertures formed in the wall of the adjacent jaw.

K denotes a bolt fitted with a wing nut for adjusting the jaws toward each other, 50 whereby their opposing inclined flanges J^b , J^b , are adapted to grip a malleable key bit Z resting upon the upstanding rib J^c . J^d indicates a spring mounted upon the screw bolt K adapted to force the jaws apart when 55 released by the adjustment of the thumb nut.

To secure the vise in the slot, formed in the end rail B^2 , an adjustable thumb screw L is provided—which in conjunction with 60 an extension rod L^1 lodged in the bore provided for the thumb screw bears against a shim L^2 lodged between the vise and the wall of the frame B^2 in which the vise is mounted.

5 It will be obvious that the relative posi-

tion of the vise in the end frame may be readily adjusted by the insertion of shims of varying thicknesses.

M, M^1 , M^2 , denote slotted channel ways formed on the top of the base plate—and 70 N, N^1 , N^2 , are adjustable posts provided with a bolt projecting through the slotted channels, fitted with a nut to secure the post when adjusted. Adjustably mounted upon the top of the respective posts N, N^1 , N^2 , 75 are stylus or guide members N^a , N^b , N^c , corresponding with the cutting edges of the tools E , E^1 , E^2 , mounted upon the shaft F, and with which they are respectively aligned. 80

O denotes a swinging lever loosely pivoted to a bolt P extending through a lug projecting from the side of the bed frame. The lever O is fitted with a pin O^1 adapted when raised by the lever to enter a groove c^3 in the movable vise frame—see Figures 85 1, 5 and 8, whereby the latter may be moved slightly along the supporting guide rails B^4 , B^5 , to guide the key blank to the respective cutting tools in conjunction with the co-operating stylus along the notched edge of the pattern key.

Having now indicated the several parts by reference letters the construction and operation of the device will be readily understood. 90

It will be noted that the duplex cutting tool E is provided with two peripheral cutting edges spaced apart adapted to simultaneously cut two notches in the bit of a key blank—the tool is also formed with annular cutting edges to cut grooves in the sides of the bit—the stylus or guide member N is laterally adjustable in its longitudinally adjustable supporting post and 100 when properly set in alignment with the cutting tool will require no further adjustment. The stylus N has spaced projecting fingers n , n , adapted to enter the grooves of the pattern key. These fingers correspond with the spaced peripheral cutting edges of the tool E—the fingers n , n , are also provided with laterally extending portions n^1 , n^1 , 105 designed to enter side grooves in a key bit. These extensions conform to the annular cutting edges projecting in opposite directions from the sides of the cutting tool.

The cutting tool E^1 is designed to cut grooves such as are indicated in the key in Figure 1 and the corresponding stylus N^3 has a finger adapted to enter the groove in the pattern key. The beveled edge of the cutting tool E^2 and its corresponding stylus 110 is designed for duplicating the V-shaped edges of keys of the Yale type. 115

To duplicate a pattern key the latter is secured between the jaw formed by the post C^1 and movable jaw C^a carried by the vise frame while the key blank is secured between the jaws formed by the post C^2 and 120 C^b . 125

C^b. The vise frame is then tilted as indicated in dotted lines in Figure 8—and shifted to a position opposite the proper stylus so that the finger of the latter may enter 5 the groove in the pattern key. The laterally movable frame B is then pushed toward the stylus and cutting tool, that the cutting tool previously set in motion through one of the driving pulleys may cut notches in the key 10 blank corresponding with those in the pattern key.

To cut ward grooves in a key bit the latter is clamped between the jaws of the vise J,—the vise being adjusted with reference 15 to the cutting tool so that the groove will be formed in proper relation to the shank of the key bit. When the blank is properly secured the frame B is moved toward the cutting tool, that the latter may mill the 20 groove in the bit.

As previously indicated to cut the annular notches formed in the edge of a Yale or other key of this type, a pattern key and a key blank are clamped in the proper supporting vises. The vise frame is then shifted so as to be in alignment with the cutting tool E², and its stylus. If necessary to adjust the frame the latter may be tilted as indicated in dotted lines in Figure 8 to pass 25 over the stylus supporting posts. When lowered the lever O is raised so that the pin P¹ enters a groove c² provided in the vise frame for its reception. The operator may then by a slight movement of the lever adjust 30 the vise frame along its supporting rods so as to cause the wedge-shaped stylus N² to follow the contour of the pattern key while forcing the key blank into contact with the cutting tool through the lateral movement 35 of the frame B.

As shown in Figures 3 and 4 the vise frame is adapted to support a key of the double bit type—the lower portion of the frame being cut away as indicated at c² to receive one of the bits while the other is being milled by the rotary cutting tool. 40

Having thus described my invention what I claim is:

1. A key milling machine, comprising a 50 shaft having cutters; a plurality of supports on which are positioned independently adjustable guides; a manually adjustable frame movable transversely to the cutter shaft; a second frame hinged to and longitudinally 55 slidable upon the first named frame and adapted to swing backwardly and forwardly to clear the guides and to position at the desired guide, and a manually operated swinging lever adapted to be detachably engaged with the hinged frame, whereby the 60 latter may be shifted longitudinally with reference to the first named frame.

2. A key milling machine, comprising a shaft having a cutter, adapted to cut ward grooves in a key bit; a manually adjustable frame movable transversely to the cutter shaft; a vise, adapted to co-ordinate with said ward cutter lodged in the wall of the transversely movable frame, comprising a pair of adjustable jaws having opposing inclined surfaces for gripping a key blank; a screw for adjusting the jaws toward each other to grip the key blank and a spring to force the jaws apart when released by the screw. 65

3. A key milling machine comprising a shaft having a cutter, adapted to cut ward grooves in a key bit; a manually adjustable frame movable transversely to the cutter shaft; a vise mounted directly upon the manually adjustable frame co-ordinating with said ward cutter adjustably lodged in the wall of the transversely movable frame, and a screw extending through the wall of the frame adapted to act upon the vise to secure 80 it in the frame when adjusted. 85

4. A key milling machine, comprising a shaft having a cutter, adapted to cut ward grooves in a key bit; a manually adjustable frame movable transversely to the cutter 90 shaft; a vise mounted directly upon the transversely movable frame, adapted to co-ordinate with said ward cutter lodged in the wall of the transversely movable frame, comprising a pair of adjustable jaws having 95 opposing inclined surfaces for gripping a key blank; an upstanding rib between the movable jaws upon which the key blank is adapted to rest; guide pins extending from one jaw into apertures provided in the opposing jaw; a screw for adjusting the jaws toward each other to grip the key blank and a spring to force the jaws apart when released by the screw. 100

5. A key milling machine comprising a 105 bed frame, a shaft having cutters thereon, adjustable guides carried by said bed frame corresponding with the cutting surfaces of said cutters, a frame movable transversely of said cutters, a vise frame carried by and longitudinally slidable upon said transversely movable frame and having a groove therein, key and key blank holding devices carried by said vise frame, a lever fixed on said bed frame to allow vertical and longitudinal movement thereof, a pin on said lever adapted to engage the groove in said vise frame upon vertical movement of the lever and to move said vise frame longitudinally with respect to the cutters upon longitudinal movement of said lever. 115

In testimony whereof, I sign this specification.

HARRY BEISSER.
